UNITED STATES PATENT OFFICE.

CHARLES J. SADLER, OF ST. LOUIS, MISSOURI, ASSIGNOR TO THE BLEES-MOORE INSTRUMENT COMPANY, OF SAME PLACE.

DESIGN FOR A SURGICAL STOCKING.

SPECIFICATION forming part of Design No. 33,447, dated October 23, 1900.

Application filed August 20, 1900. Serial No. 27,502. Term of patent 14 years.

To all whom it may concern:

Be it known that I, CHARLES J. SADLER, of the city of St. Louis, in the State of Missouri, have invented and produced a new and original Design for a Surgical Stocking, of which the following is a full, clear, and exact description, reference being had to the accompanying drawings, forming a part hereof.

In the drawings, Figure 1 is a side elevation of my newly-invented design. Fig. 2 is a section on the line *a a* of Fig. 1. Fig. 3 is a detail elevation showing a portion of the body of the stocking enlarged.

The leading or material feature of my design consists of a series of horizontal cylindrical bars extending around the stocking and projecting almost entirely upon the exterior thereof, and the exteriors of said horizontal cylindrical bars are covered by stitches, the exterior of which presents the appearance of inverted heart-shaped bodies arranged in horizontal rows and having between the said rows inverted-V-shaped bodies.

The leg, ankle, and foot of the stocking

have the usual contour, and there is a V-shaped opening 4 in the heel-section.

5 indicates parallel horizontal bars, which project almost wholly upon the exterior of the stocking, leaving the interior smooth and even and giving to the exterior a corrugated appearance, (see Fig. 2,) and the exteriors of said horizontal bars are covered by stitches 6, the exterior of which presents the appearance of inverted heart-shaped bodies arranged in horizontal rows and having between the said rows inverted-V-shaped bodies 7, formed by the interior threads of the stocking being interwoven with the exterior threads which form the stitches 6.

I claim—

The design for a surgical stocking, substantially as herein shown and described.

In testimony whereof I affix my signature in presence of two witnesses.

CHARLES J. SADLER.

Witnesses:
